CLAIM

The ornamental design for a display screen or portion thereof with graphical user interface, as shown and described.

DESCRIPTION

The FIGURE is a front view of the claimed design for a display screen or portion thereof with graphical user interface.

The uneven-length broken lines depict boundaries of the claimed design and form no part thereof. The even-length broken lines showing the rest of the display screen or portion thereof with graphical user interface depict environmental structure and form no part of the claimed design.

1 Claim, 1 Drawing Sheet
